CLAIM

The ornamental design for a safety gate, as shown and described.

DESCRIPTION

FIG. 1 is a front, top and right side perspective view of a safety gate, showing my new design;

FIG. 2 is a rear, bottom and left side perspective view thereof;

FIG. 3 is a detached state perspective view of the safety gate;

FIG. 4 is another detached state perspective view of the safety gate;

FIG. 5 is another detached state perspective view of the safety gate;

FIG. 6 is a front view thereof;

FIG. 7 is a rear view thereof;

FIG. 8 is a left side view thereof;

FIG. 9 is a right side view thereof;

FIG. 10 is a top plan view thereof; and

FIG. 11 is a bottom plan view thereof.

FIG. 12 is an enlarged view of portion 12 shown in FIG. 1.

FIG. 13 is an enlarged view of portion 13 shown in FIG. 1.

FIG. 14 is an enlarged view of portion 14 shown in FIG. 1; and,

FIG. 15 is an enlarged view of portion 15 shown in FIG. 2.

The dash-dash broken lines shown in the drawings illustrate portions of the safety gate that form no part of the claimed design. The dot-dash broken lines indicate areas of the figures shown enlarged and form no part of the claimed design.

1 Claim, 15 Drawing Sheets
